UNITED STATES PATENT OFFICE

2,468,156

POT TYPE OIL BURNER

Howard C. Baity, Detroit, Mich., assignor to
Michigan Tank & Furnace Corporation, De-
troit, Mich., a corporation of Michigan

Application August 21, 1945, Serial No. 611,817

1 Claim. (Cl. 158—91)

1

The invention relates to oil burner apparatus of the vaporizing pot burner type.

The invention has for one of its objects to provide an improved burner which is so constructed that it produces a clean, uniform flame.

The invention has for another object to provide an improved burner which is so constructed that in the event that the oil or oil vapor is ignited when the burner is flooded, puffing or kicking back of the burner is avoided.

The invention has for a further object to provide an improved burner which is so constructed that the flame is directed radially inwardly and toward the center of the burner at its top.

With these and other objects in view, the invention resides in the novel features of construction and combinations and arrangements of parts as more fully hereinafter set forth.

In the drawings—

Figure 1 is a side elevation, partly in section, of a portion of an oil burner apparatus having a burner embodying the invention;

Figure 2 is a cross section on the line 2—2 of Figure 1.

The oil burner apparatus, which is partly illustrated in the present instance, is a hot water heater in which the tank 1 has the inner cylindrical tube 2 which forms the combustion chamber. 3 is the burner which comprises a sheet metal shell having the side wall 4 and integral bottom wall 5 and top wall 6 preferably in the nature of a casting resting upon the upper end of the side wall 4. The top wall has the downwardly extending annular flange 7 sleeved within the side wall 4 and the upwardly extending annular flange 8 sleeved within the tube 2. The top wall is provided with the central opening 9 for placing the space inside the burner in communication with the combustion chamber formed by the tube. 10 and 11 are sheet metal baffles spaced from each other and the bottom and top walls of the burner, the baffle 10 having the central opening 12 and the baffle 11 having the central opening 13 of appreciably greater diameter than the opening 12. The side wall 4 is provided with the annular series of primary air inlet openings 14 below the lower baffle 10 and also with the annular series of primary air inlet openings 15 and 16 above the lower baffle 10, the openings 16 being below and adjacent to the upper baffle 11. The side wall 4 is also provided with the annular series of secondary air inlet openings 17 above the upper baffle 11.

The burner is also provided with the wall 18 which may be formed integral with or separately

2

from the upper baffle 11. As illustrated in the present instance, it is formed separately and fixedly secured to the upper baffle as by being welded thereto. More in detail, the wall 18 has the cylindrical portion 19 which is sleeved within and welded to the cylindrical portion 20 of the upper baffle. The wall 18 also has the tapering portion 21 which extends upwardly and radially inwardly of the burner from the cylindrical portion 19 and the cylindrical portion 22 which extends upwardly from the tapering portion 21 and abuts the top wall 6. The wall 18 therefore cooperates with the side wall 4 and the top wall 6 to form an air chamber communicating with the air outside the burner through the openings 17. The wall 22 is formed with the annular series of openings 23 which are preferably of the same size as the openings 17 and which are spaced a substantial distance below the upper edge of the cylindrical portion 22.

The sizes of the primary and secondary air inlet openings are such that the oil which enters the burner through the oil inlet 24 vaporizes and rises through the central openings 12 and 13 of the baffles and finally mixes with the secondary air above the baffles to produce a clean, efficient flame, the secondary air being sufficient to assure complete combustion. The flame starts immediately adjacent the cylindrical portion 22 and projects radially inwardly therefrom.

For the purpose of avoiding kicking or puffing back in the event that the oil in the burner is ignited when the burner is flooded, the top wall 6 is formed with the annular extension 25 radially inwardly beyond the cylindrical portion 22 and terminating in the depending annular flange 26, the lower edge of which is preferably substantially in line with the uppermost edge portions of the openings 23. The annular extension and depending flange also serve to direct the flame radially inwardly from the cylindrical portion 22 to the opening 9 bounded by the depending flange, after which the flame rises, the arrangement being such that direct contact of the flame with the inner tube 2 is eliminated thereby avoiding direct burning of this tube.

What I claim as my invention is:

50 A pot type oil burner having a cylindrical side wall, a circular bottom wall, an annular top wall, annular upper and lower baffles spaced from each other and said bottom and top walls and having central openings therethrough, and an inner wall 55 above said upper baffle inside said side wall and

cooperating with said side wall and top wall to form an annular air chamber, said inner wall having openings between its upper and lower edges for the passage of air from said chamber into the space inwardly of said inner wall, said top wall having a portion extending inwardly toward the axis of said burner beyond said inner wall and terminating in a depending annular flange with its lower edge substantially in line with the uppermost edge portions of the openings in said inner wall, said cylindrical side wall having primary air inlet openings below and above said lower baffle and secondary air inlet openings to said chamber.
